UNITED STATES PATENT OFFICE.

RUDOLPH VANA, OF BROWNSVILLE, TEXAS.

MUSICAL INSTRUMENT.

Application filed January 12, 1926. Serial No. 80,719.

This invention relates to certain new and useful improvements in musical instruments of the stringed type, wherein a manually shiftable member in the form of a hammer or block constructed of bell metal is movable over the strings that are played in a manner similar to a guitar, the shiftable block being formed of bell metal increasing the tone volume and longevity thereof.

10 A further object of the invention is to provide a stringed musical instrument wherein a single string wire is employed, the single wire being looped around a freely turning brass roller on a supporting post 15 with the ends thereof secured to a tuning key to be operated for attaining the proper pitch.

With the above and other objects in view that will become apparent as the nature of 20 the invention is better understood, the same consists of the novel form, combination and arrangement of parts hereinafter more fully described, shown in the accompanying drawings and claimed.

25 In the drawings, wherein like reference characters designate corresponding parts throughout the several views,

Figure 1 is a top plan view of a stringed musical instrument constructed in accordance with the present invention,

Figure 2 is a side elevational view thereof,

Figure 3 is an enlarged fragmentary top plan view,

Figure 4 shows side and end elevational 35 views of the hammer or block to be moved over the strings,

Figure 5 is a side elevational view of the handle detached from the hammer or block,

Figure 6 is a perspective view of the hammer and handle assembled,

Figure 7 shows top plan and side elevational views of a mute to be attached to the hammer,

Figure 8 is a fragmentary side elevational 45 view of the outer end of the instrument with another form of mute attached to the instrument,

Figure 9 is a bottom plan view of the mute shown in Fig. 8,

Figure 10 is a fragmentary top plan view 50 of the outer end of the mute showing the tuning key to which the string is attached, and

Figure 11 is a detail sectional view showing the guide rollers over which the string passes.

The case of the instrument, preferably being of the design shown in Fig. 1 embodies upper and lower walls 1 and 2 connected by a side edge wall 3, the case being supported upon a plurality of seats 4, preferably of ball formation as shown in Fig. 2 with horizontal unalined grooves 5 cut through opposite sides of the ball feet to form a spring and to increase vibrations of the case during the playing of the instrument and to utilize such vibration in producing tremolo tune.

The instrument embodies a single string arranged in looped formation as shown in Fig. 3, the string 6 being looped intermediate the ends thereof to enclose a roller 7 that is rotatable on the stud 8 and be retained in position thereon by seating in the roller groove 7^a while the two free ends of the looped string are anchored to the tuning key 9. As shown more clearly in Figs. 3, 8 and 11 a bracket including a base plate 10 is secured as at 11 to the upper wall 1 of the case and carries parallel side walls 12 in which a cross pin 13 is set. A roller 14 is supported on the pin 13 and is annularly grooved as at 15 to confine and guide the two sides of the looped string 6.

As shown in Fig. 10, the upper wall 1 of the case is provided with a pair of spaced openings 16 separated by the central partition 18 and said pin 9 is journaled in the partition wall 18 and one side 3 of the case. The base plate 10 of the bracket is provided with a pair of openings 19, each aligned with an opening 16, through which the string 6 extends as shown in Fig. 3. The outer end of the tuning key 9 carries a pinion 20 to be engaged by the worm 21 upon the shaft 22 that is journaled in the bracket 23 at the side 3 of the case, this construction being clearly shown in Fig. 8. The upper end of the shaft 22 is provided with a knob 24 to facilitate operation thereof.

As shown in Figs. 1 and 3, the upper wall 1 of the case has painted, printed or otherwise impressed thereon a music clef 25 with note characters 26 and several octaves of note letters 27. The two strings 6 are manipulated or played similar to a guitar 105 or mandolin and in lieu of the usual fret bars, a resident block or hammer is moved over the wires to obtain the proper notes. The hammer is shown in detail in Figs. 4 to 6 and is preferably in the form of a cylindrical member 28 having one end thereof tapered as at 29 substantially to a knife

edge with spaced notches 30 at the edge for receiving the spaced sides of the string 6. The member 28, substantially midway the ends thereof is longitudinally split in cross directions as at 31 to provide four vibrating members 32. To increase the tone volume and quality of the instrument, the hammer 28 is preferably formed of bell metal which will sound when the string 6 is played. 5 The metal from which the hammer is made is the usual alloy for making bell metal. The hammer 28 is carried by the handle 33 shown in detail in Fig. 5 wherein the tang 34 of the handle is offset at an angle to be received in the angularly disposed socket 35 formed in the hammer so that the handle 33 can be positioned laterally of the case and string 6 when the grooves 30 in the knife edge of the tapered end of the hammer engage the sides of the string 6. By shifting the hammer 28 along the string 6 relative to the notes upon the cleft 25 the desired note is obtained and if desired, the pick 36 shown by dotted lines in Fig. 6 may 10 be employed in manipulating the string. As shown in Figs. 1 and 3, a metallic plate 37 is secured to the upper wall 1 of the case adjacent the stud 8 to prevent marring of the wall surface and finish when the instrument is played with a pick or the like and to fasten to the plate different attachments for 15 playing.

A mute may be attached to the hammer 28 and moved therewith over the string 6, the mute being illustrated in Fig. 7 in the form of a wire frame having curved spaced legs 38 connected by a reversely curved portion 39 that is attached to the felt 40 as at 41. The tapered end 29 of the hammer 20 is provided with spaced openings 42 that receive the spaced legs 38 and dispose the felt 40 for contact with the spaced sides of the looped string 6 rearwardly of the hammer. It is also intended that the mute of the form 25 shown in Figs. 8 and 9 be attached to the case, this mute being formed of a resilient stick bent upon itself to form opposite sides 43 and 44 connected by an intermediate bent or loop 45, the end of the side 44 being 30 notched as at 46 to be removably positioned beneath the screw 11 shown in Figs. 3 and 8.

The felt 47 carried by the side 44 is positioned for contact with the string 6 while the side 43 extends outwardly between the 35 two sections of the string. When the hammer 28 is moved over the wire 6, the same may engage the looped end 45 of the mute to displace the felt 47 from contact with the wire to displace the mute from the path of 40 movement of the hammer.

When the hammer 28 is moved over the string 6 with the two sections of the string lying in the groove 30 in the lower edge of the tapered end 29 of the hammer, the latter 45 may be shifted to the desired position rela-

tive to the cleft and operate in lieu of the usual fret. A suitable implement, such as a pick may be employed in manipulating the string and with the angularly disposed tang 34 upon the end of the handle 3, the hand 70 that moves the hammer may be displaced laterally of the string to permit freedom of movement of the other hand in striking the string. Also, the handle 33 may be shifted relative to the hammer 28 to dispose the 75 hand of the operator directly above the strings so that the instrument may be played with only one hand. The string 6 being in the form of a loop and a single strand, extends around the roller 7 on the stud post 80 8 with its free ends attached to the tuning key 9 and the desired pitch for the string may be obtained by manipulating the key.

While there are herein shown and described the preferred embodiments of the 85 present invention, it is nevertheless to be understood that minor changes may be made therein without departing from the spirit and scope of the invention as claimed.

What is claimed is:—

1. In a musical instrument of the character described, a case, a single looped string, a tuning key to which the ends of the string are attached, a hammer of bell metal movable over the string to operate in lieu of the usual frets, and said hammer having a tapering end grooved to receive the string.

2. In a musical instrument of the character described, a casing, a single looped string, a tuning key to which the ends of the string are attached, a hammer of bell metal movable over the string to operate in lieu of the usual frets, a guide roller for the center and ends of the string supported above the upper wall of the case, and said hammer having a tapering end grooved to receive the string.

3. In a musical instrument of the character described, a case, a single looped string, a tuning key to which the ends of the string are attached, a hammer of bell metal movable over the string to operate in lieu of the usual frets, said hammer having a tapering end grooved to receive the string, and with the opposite upper end split crosswise and longitudinally to increase vibrations thereof when the string is played.

4. In a musical instrument of the character described, a casing, a single looped string, a tuning key to which the ends of the string are attached, a hammer of bell metal movable over the string to operate in lieu of the usual frets, a guide roller for the center and ends of the string supported above the upper wall of the case, said hammer having a tapering end grooved to receive the string, and with the opposite upper end split crosswise and longitudinally to increase vibrations thereof when the string is played.

5. In a musical instrument of the character described, a case, a single looped string, a tuning key to which the ends of the string are attached, a hammer of bell metal movable over the string to operate in lieu of the usual frets, a guide roller for the center and ends of the string supported above the upper wall of the case, said hammer having a tapering end grooved to receive the string, with the opposite upper end split crosswise and longitudinally to increase vibrations thereof 55
- 10 when the string is played, the tapered end of said hammer having spaced openings therein, and a mute embodying wire legs received in said openings and having a felt positioned for contact with the string. 60
- 15 6. In a musical instrument of the character described, a casing, a single looped string, a tuning key to which the ends of the string are attached, a hammer of bell metal movable over the string to operate in lieu of the usual frets, a guide roller for the center and ends of the string supported above the upper wall of the case, said hammer having a tapering end grooved to receive the string, with the opposite upper end split crosswise and longitudinally to increase vibrations thereof when the string is played, and a handle for the hammer having an offset tang to dispose the handle laterally of the string when the hammer is operatively positioned. 65
- 20 7. In a musical instrument of the character described, a case, a single looped string, a tuning key to which the ends of the string are attached, a hammer of bell metal movable over the string to operate in lieu of the usual frets, a guide roller for the center and ends of the string supported above the upper wall of the case, said hammer having a tapering end grooved to receive the string, with the opposite upper end split crosswise and longitudinally to increase vibrations thereof when the string is played, the tapered end of said hammer having spaced openings therein, and a mute embodying wire legs received in said openings and having a felt positioned for contact with the string. 70
- 25 8. In a musical instrument of the character described, a case, a single looped string, a tuning key to which the ends of the string are attached, a hammer of bell metal movable over the string to operate in lieu of the usual frets, said hammer having a tapering end grooved to receive the string, with the opposite upper end split crosswise and longitudinally to increase vibrations thereof when the string is played, and a mute removably attached to the upper side of the case at the outer end and being constructed for displacement from the string when engaged by the hammer. 75
- 30 9. In a musical instrument of the character described, a casing, a single looped string, a tuning key to which the ends of the string are attached, a hammer of bell metal movable over the string to operate in lieu of the usual frets, said hammer having a tapering end grooved to receive the string, with the opposite upper end split crosswise and longitudinally to increase vibrations thereof when the string is played, and a mute removably attached to the upper side of the case at the outer end and being constructed for displacement from the string when engaged by the hammer. 80
- 35 10. In a musical instrument of the character described, a casing, a single looped string, a tuning key to which the ends of the string are attached, a hammer of bell metal movable over the string to operate in lieu of the usual frets, a guide roller for the center and ends of the string supported above the upper wall of the case, said hammer having a tapering end grooved to receive the string, with the opposite upper end split crosswise and longitudinally to increase vibrations thereof when the string is played, and a mute removably attached to the upper side of the case at the outer end and being constructed for displacement from the string when engaged by the hammer. 85
- 40 45 8. In a musical instrument of the character described, a casing, a single looped string, a tuning key to which the ends of the string are attached, a hammer of bell metal movable over the string to operate in lieu of the usual frets, said hammer having a tapering end grooved to receive the string, with the opposite upper end split crosswise and longitudinally to increase vibrations thereof when the string is played, and a handle for the hammer having an offset tang to dispose the handle laterally of the string when the hammer is operatively positioned. 90

In testimony whereof I affix my signature.
RUDOLPH VANA.
